UNITED STATES PATENT OFFICE.

EDWARD JOHN RIDGWAY, OF HEMPSTEAD, NEW YORK.

DESIGN FOR A COVERED DISH.

Application filed September 9, 1924. Serial No. 10,723. Term of patent 7 years.

To all whom it may concern:

Be it known that I, EDWARD JOHN RIDGWAY, a subject of the King of Great Britain and Ireland, residing at Hempstead, Long Island, in the county of Nassau, State of New York, have invented a new, original, and ornamental Design for Covered Dish, of which the following is a specification, reference being had to the accompanying drawings, forming part thereof.

Fig. 2 is a side elevation.

Fig. 3 is a bottom plan view.

It is to be understood that in each of the three figures, the decorations shown on half the figure, actually extend around the entire circumference of the article.

I claim

The ornamental design for a covered dish, as shown and described.

EDWARD JOHN RIDGWAY.
